UNITED STATES PATENT OFFICE.

RALPH C. SEYMOUR, OF LARCHMONT, NEW YORK, ASSIGNOR TO GOSS PRINTING PRESS COMPANY, A CORPORATION OF ILLINOIS.

WEB-CUTTING MACHINE.

1,248,023.

Specification of Letters Patent. Patented Nov. 27, 1917.

Original application filed August 21, 1913, Serial No. 785,885. Divided and this application filed June 10, 1914. Serial No. 844,151.

To all whom it may concern:

Be it known that I, RALPH C. SEYMOUR, a citizen of the United States, residing at Larchmont, in the county of Westchester 5 and State of New York, have invented certain new and useful Improvements in Web-Cutting Machines, of which the following is a specification.

The invention relates to sheet handling 10 machines, and more especially for machines for cutting sheets from a web.

The objects and advantages of the invention will in part be set forth hereinafter and will in part be obvious herefrom, and 15 such objects and advantages are attained or effectuated by the means or instrumentalities set forth in the appended claims.

The invention consists in the novel parts, constructions, arrangements, combinations 20 and improvements herein shown and described.

The accompanying drawings, referred to herein and forming a part hereof, illustrate one embodiment of the invention, the same 25 serving in connection with the description to explain the principles of the invention.

Of the drawings:

Figure 1 is an elevation, with the front 30 frame removed of a machine embodying the principles of the invention;

Fig. 2 is an elevation, looking at Fig. 1 from the right;

Fig. 3 is an elevation looking at Fig. 1 from the left; and

Fig. 4 is an enlarged fragmentary view 35 of the slitter shown near the top in the preceding figures.

Referring to the accompanying drawings, illustrating by way of example one embodiment of the invention, a mechanism is shown 40 adapted to receive a running web *x*, although in many of its aspects the invention is adapted to coöperate also upon sheets. In accordance with certain features of the 45 invention, a plurality of webs may be fed or run side by side instead of a single web *x* as shown in the drawing.

Means are provided by the invention for cutting transversely the paper fed to the 50 machine, cutting a portion of the width of the paper into sheets of one length and the remainder of said width into sheets of a different length. In accordance with one feature of the invention, sheets of a shorter

length are a submultiple of sheets of a longer 55 length. Also in connection with certain features of the invention enumerated, there is provided by the invention means for longitudinally separating the portions of the web which have been cut transversely into different sheet lengths, thereby totally severing such sheets one from another.

As exemplified by the illustrated embodiment, a machine and instrumentalities included therein are provided adapted to operate upon a web *x* coming in at the upper part of the machine (see Fig. 1) from a printing press or other machine. As embodied, the web is cut transversely half way, or to the center line of the web, the 70 cuts in one half of the web, so considered, being more frequent than in the other, and in the present embodiment, one half of the web is cut into sheets of half the length of the sheets into which the other half of the 75 web is cut. That is, the transverse cuts in one half of the web are made with double the frequency that they are made in the other half.

Referring to the drawings, suitable feed- 80 ing-in means for the web are provided, such as sets of rollers, 1 and 2, mounted, respectively, on corresponding shafts 3 and 4. Running over said rollers are a series of tapes 5. Suitable tightening devices for the 85 tapes 5 may be provided, such as a series of rollers 6 bearing on the tapes and carried on a shaft 7. Said shaft 7 is mounted in a pair of pivotally mounted arms 9, which may be spring-pressed or yieldingly acted 90 upon in a suitable manner.

The embodied form of cutting means for the paper comprises a shaft 10, rotatably mounted in the machine frame, and carrying a plurality of rotating disks 11. Arranged along the shaft 10, and running from one disk 11 to another, is a web or blade holder 12, suitably recessed to receive the knife or shearing blade 13. On the other side of the paper there is rotatably mounted 100 in the machine frame, a shaft 14, carrying a plurality of disks or heads 15. A web or support 16 extends along the shaft 14 and from one disk 15 to another, and is suitably recessed to hold the companion knife or 105 shear blade 17. In such embodied form, this set of coacting shearing blades 13 and 17 extend entirely across the machine, that is,

across the entire width of the paper as it is fed past these rotary cutters.

As a part of the embodied rotary cutter device there is provided a web or support 20, extending longitudinally of the shaft 10 and from one disk or head 11 to another. Said web 20 is recessed to receive a shearing blade or other suitable cutting device, and in accordance with one feature of the invention 10 a cutting or shearing blade 21 is removably mounted in the holder or web 20. Such removable mounting is shown as bolts and nuts 22 which pass through the holder 20 and the blade 21 to hold it in position. 15 The blade or cutter 21 is thus removable at pleasure, and one side or length of blade or cutter may be substituted for another. In the embodied form, the blade 21 extends from the side of the paper to the center 20 thereof and is adapted to make a transverse cut from the edge to the center, that is, half way across the paper.

On the opposite side of the paper, a web or blade support 23 is likewise arranged 25 longitudinally of the corresponding shaft 14, and extending from one head 15 to another, and is recessed to hold the blade 24. This shearing blade 24 is likewise removably mounted, and bolt and nut fastenings 30 25 are shown for this purpose. As embodied, the blade 24 is of the same size or length as the blade 21, and acts oppositely thereto, that is, it co-operates therewith to make a cut in the paper transversely half way across. The blades 13 and 17 may also be made removable if desired.

If the blades 21 and 24 are half the width of the web, as shown, and the blades 13 and 17 are the full width of web, it will be seen 40 that for each complete rotation of the shafts 10 and 14, the web will receive one cut or severance completely across its width, and that one half of the web or sheet, considered transversely, will receive a second cut 45 or severance, a half revolution apart from the cut made by the blades 13 and 17. In other words, one half of the web or sheet will be cut transversely twice as often and 50 into half the length of the other half of the web or sheet.

If two webs are run side by side, the sheets would be completely severed from each other by the transverse cuttings, one set or series of sheets being of different size from the other. Means are provided by the invention, co-operating with the transverse severing means, for longitudinally severing a full width web, so as to separate it into the sheets of different lengths. In the embodied form 55 of such means, a shaft 30 is rotatably mounted in the machine frame, said shaft carrying a rotary slitting disk 31. A suitable shaft 4 is likewise mounted in the machine frame, and carries a grooved disk 33, the 60 disk 31 and the disk 33 co-operating together 65

to slit the web π longitudinally and centrally.

Means are provided for directing the sheets of different sizes to the subsequent mechanisms, and in the embodied form 70 thereof, a series of throat-bars 34 are mounted upon a shaft 35, and an opposing and co-operating set of throat-bars 36 are mounted upon a rod or shaft 37, the sheets passing between these two sets of throat-bars. 75 Mounted beyond or below the cutting devices, and in co-operative relation with the throat-bars, is a set of rotating disks or rollers 38 carried on a shaft 39. Operating against the series of disks or rollers 39 is 80 a similar set of disks or rollers 40, carried on shaft 41. Suitable driving means (not shown) for these disks are provided. The end of the web is received between these two sets of driven disks or rollers 38 and 40, and 85 directed forward through the machine. These disks or rollers may be provided, respectively, with cut-away portions 42 and 43, to give a prompt and full release to the tail of the sheets.

In the embodied form there is also provided a second group of co-operating rollers or disks, comprising a set of rollers or disks 50, carried upon a shaft 51, suitably journaled in the machine frame. Co-operating 95 with the set of disks 51 in this second group is a series of disks or rollers 52, carried by a shaft 53, likewise journaled in the machine frame. Suitable driving means (not shown) are provided for the disks.

The disks 50 and 52 are provided with cut out portions 54 and 55, respectively, similar to the other series of disks. If found desirable or convenient, one group of the opposed rollers or disks may be rendered 105 inactive, and further, in accordance with one feature of the invention, a part of one, or of either, group of opposed rollers or disks may be rendered inoperative in any suitable manner. By way of example, the 110 half of two opposed series of disks, considered transversely of the machine, could have their cut away or lower portions alined toward, or facing, the paper as it is fed therebetween. Such disks could then be 115 held from rotation with their respective shafts, being released therefrom by suitable means, and as a suitable series of set screws, or by a key or keys, as might be found suitable or convenient.

Means are also provided for throwing off, or rendering inoperative, an entire group or set of the opposed disks. For this purpose, the shaft 51 is provided with slideable bearings in the machine frame, of suitable 125 form, said bearings being adjustable by means of threaded rods 58, provided with suitable nuts 57, and acted upon by corresponding springs 58. Similar devices and connections are provided for the series of 130

disks 52, comprising screw-threaded rods 59, having, respectively, nuts 60, and springs 61.

By the construction and arrangement just described the two groups of forwarding disks could operate upon sheets of one length, and one group thereof could operate upon sheets of another length if desired, or one entire group of the opposed disks can be thrown out of action entirely across the width of the web or paper.

Suitable means are provided for receiving the sheets, and for separately receiving and disposing of the sheets of different lengths, one form of such devices includes folding and collecting mechanism, the same being claimed and fully described in the parent application Ser. No. 785,885 of which the present application is a division, the same reference numerals being used in the parent application as are shown on the folding and collecting mechanism of the drawings herewith.

Means are provided by the invention for severing the folded product from the cylinder 80, especially where there are a plurality of folding mechanisms 90 for longitudinally folding sheets delivered thereto from the cylinder 80. Such a severing mechanism is shown in Fig. 1 only, and as comprising the rotary slitter 79 carried on shaft 78, mounted in the machine frame, and driven in suitable manner, and coöperating with the cylinder 80. If desired, it could be located to coöperate with cylinder 70 instead. If desired, the slitter or slitters 31 may be used instead for producing the same product.

Concerning the manner of operation of the herein described mechanism, many features thereof will be clear from what has already been said.

The machine may be considered as operating upon a single web w , as shown in Fig. 1, said web being directed through the rotary cutter mechanism. If but a single pair of cutting blades be mounted in the rotary cutting mechanism, and they extend all the way across the width of the web, the sheets cut will be what may be conveniently termed double length sheets. Considering further the sheets as being forwarded to cylinder 70, the cut sheets are forwarded by the forwarding disks and throat bars, to said cylinder 70, and are taken by the grippers 72. If the cylinder 72 is not collecting, the single sheet will be folded off therefrom into one of the sets of folding jaws 82 or 83 upon the cylinder 80. The sheets so folded may be delivered to the carrier 100, in which case the sheet is delivered with all the edges free or cut. The sheet so folded by cylinder 80, may be slitted longitudinally either in the web, as by the slitter, or slitters, 31, 33, or sheet slitting mechanism may be employed such as the rotary slitter 79.

The cylinders of the printing press may be arranged to take the plates with the page length extending along the cylinder, or with the page length extending about the cylinder, to harmonize with the particular kind of product desired as finally cut and folded. Suitable stripping devices may be used with either mode of delivery from the cylinder 80, which may be similar to the strippers 123, or of other suitable or convenient form.

If it be still assumed that one pair of cutting or shearing blades be used in the rotary cutter mechanism and the double length sheets are cut from the web, the cylinder 70 sheets are cut from the web, the cylinder 70 may be used as a collecting cylinder. It will be assumed that said cylinder collects two sheets, the second upon the first. In this case only one of the sets 82 or 83 of the folding jaws on cylinder 80 are used for folding off the sheets from cylinder 70. If the folded product be delivered from the cylinder 80 to the conveyer 100, the product will consist of a signature of eight pages, open or cut all around. If the product is forwarded from the cylinder 80 to the folder or folders 90, the product will consist of one or more signatures having a closed or folded end and consisting of 16 pages.

If two sets of full width shearing or cutting blades are employed in the rotary cutter device, that is, cutting the web transversely for its full width, the sheets produced will be of half the length of the long sheets previously referred to. Such sheets are forwarded to the collecting cylinder 105 and after collecting, a collected group of sheets is delivered to the folding mechanism, or mechanisms, 111, are registered by the stop 122, and are folded to give a signature having all cut edges. It will thus be seen that among the possible products are either a closed and sixteen page signature from the folder 90, or a sixteen page signature from the folder 111 with all cut edges.

Both a long set of shearing blades and a short set of shearing blades may be used in the cutting mechanism, and one or more short sheets run on the other side of the machine, depending on its width and duplication of the devices, and a plurality of various products may be simultaneously delivered, and each product delivered at the full speed of the press.

Suitable tapes running in coöperation with the tapes 5, from the opposite side of the web therefrom may be provided, but are omitted from Fig. 1 for the sake of clearness in showing other parts of the mechanism, but are shown in Figs. 2 and 3.

It will be understood that the various mechanisms may be advanced or timed in a suitable manner for the various purposes and products. It will be also understood

that the various adaptations and ways of operating are illustrative in character and not restrictive.

This application is a division of my application Ser. No. 785,885, filed August 21, 1913.

The invention, in its broader aspects, is not limited to the particular constructions shown, nor to any particular constructions 10 by which it has been or may be carried into effect, as many changes may be made in the construction without departing from the main principles of the invention and without sacrificing its chief advantages.

15 What I do claim as my invention and desire to secure by Letters Patent, is:—

1. A web cutting machine including in combination web supplying means and means for making successive shearing cuts

20 in the web substantially perpendicularly to the side edges thereof, said cutting means comprising severing devices adapted to make cuts extending for different distances across the web.

25 2. A web cutting machine including in combination web supplying means and means for making successive shearing cuts in the web substantially perpendicularly to the side edges thereof, said cutting means comprising severing devices adapted to make cuts extending for different distances across the web and means for longitudinally slitting the web, the longitudinal and transverse cuts uniting to produce sheets of different lengths.

30 3. A web cutting machine including in combination web supplying means and rotary means for making successive shearing cuts in the running web substantially perpendicularly to the side edges thereof, said means comprising a plurality of cutting devices for making successive cuts extending for different distances across the web.

45 4. A web cutting machine including in combination web supplying means and rotary means for making successive shearing cuts in the running web substantially perpendicularly to the side edges thereof, said means comprising a plurality of cutting devices for making successive cuts extending for different distances across the web and means for longitudinally slitting the web, the longitudinal and transverse cuts uniting to produce sheets of different lengths.

50 5. A web cutting machine including in combination web supplying means and

means for making successive shearing cuts in the web substantially perpendicularly to the side edges thereof, successive cuts extending for different distances across the web, means for longitudinally slitting the web, the longitudinal and transverse cuts uniting to produce sheets of different lengths and a plurality of sheet receiving devices 65 alternatively operative to receive the sheets of different length.

6. A web cutting machine including in combination means for feeding a running web, means for longitudinally slitting the 70 running web, and means for severing the running web entirely across, and means for severing the running web from the outer edge to the longitudinal slit at intervening points between said cuts entirely across the 75 web.

7. A web cutting machine including in combination means for feeding a web, means for longitudinally slitting the web, and means for severing the web entirely across, 80 and means for severing the web from the outer edge to the longitudinal slit at intervening points between said cuts entirely across the web.

8. A web cutting machine including in 85 combination web supplying means, co-operating rotary cutting devices for transversely shearing the web and making the successive transverse cuts alternately partially across the web and then entirely across the web 90 and longitudinal slitting means uniting the various transverse cuts to produce sheets of different length.

9. A web cutting machine including in combination web supplying means, a rotary 95 cutting mechanism having two members each carrying one blade of a plurality of pairs of blades, the different pairs of blades being of different lengths.

10. A web cutting machine including in 100 combination web supplying means, a rotary cutting mechanism having two members each carrying one of a plurality of pairs of blades, the different pairs of blades being of different lengths, and a longitudinal slitter 105 co-operating therewith to completely sever the web into sheets.

In testimony whereof, I have signed my name to this specification, in the presence of two subscribing witnesses.

RALPH C. SEYMOUR.
